ELECTRICAL REPRODUCING DEVICE

Curtis P. Mitchell, Cincinnati, Ohio, assignor to
 The Palmer Company, Cincinnati, Ohio, a corporation of Ohio

Application December 4, 1931, Serial No. 579,038

4 Claims. (Cl. 177—351)

This invention relates to electrical apparatus and is particularly directed to an apparatus or system for electrically reproducing motion at a location remote from the location at which it is applied. More specifically, the invention is utilized as an electrically operated system for reproducing, recording, or showing temperatures at points removed from the environment, the temperature of which is being determined.

10 It is an object of this invention to provide an apparatus or system for electrically reproducing thermostatically detected temperature changes by means of a unit placed at the environment of heat change which may be a theatre, an oven, etc., and connecting this unit by electrical means to a receiving unit which may be located at a remote point such as the outside of the theatre or the recording room of a bakery or extremely remote points, the receiving apparatus receiving 20 signals from the sending device by electrical control and converting them into mechanical movement which is effective for temperature record or display purposes.

It is a further object to provide apparatus of 25 this character which is extremely sensitive and which, therefore, transmits the very slightest change in temperature and immediately displays or records the change simultaneously with the occurrence thereof. Moreover, it is arranged 30 that, in the event of power failure in the electrical connecting means between the sending and receiving devices, these devices will automatically operate when the power is restored for quickly and accurately reproducing the temperature 35 reading existing at the time of power restoration without requiring any resetting of the apparatus. For this purpose, the synchronous arrangement of the devices is not destroyed by power failure and the relation of the position of 40 the temperature actuated element relative to the temperature is constantly maintained.

It is a more general object of this invention to 45 provide a system and apparatus for electrically reproducing relative movement at a location remote from a location where the motion is created and further to include the provision of means for effecting the aforesaid electrically reproduced movement in reverse directions as determined by 50 the direction of movement at the source or initially.

Other objects and certain advantages will be 55 more fully apparent from a description of the accompanying drawings, in which:

Figure 1 is a wiring diagram illustrating the

electrical elements and connections of the present apparatus and system.

Figure 2 is a top plan view of the sending unit showing the mechanical construction thereof in detail.

Figure 3 is a side view of Figure 2, further detailing the sending unit.

Figure 4 is a front view, partly broken away, of the recording unit.

Figure 5 is a side view of Figure 4, certain parts 10 thereof being shown in section for more fully illustrating the structure.

Figure 6 is a bottom view of the recording unit.

Figure 7 is a sectional view taken on line 7—7, Figure 6, detailing the electrical connections to 15 the conductor fingers which control the operation of the recording motor.

Figure 8 is a diagrammatic view illustrating a portion of the wiring for the purpose of showing the voltage connections for alternate operation 20 of the motors, this view illustrating the sending motor in operation.

Figure 9 is a diagrammatic view similar to Figure 8, but showing the receiving motor in operation and the connection effective for preventing concurrent operation of the sending motor.

In practice, the present invention is constructed in two units, namely a sending unit 10 and a recording unit 11, connected by electrical wiring, 30 the distance between these units being immaterial since it may range from adjacent locations to very remote locations. The apparatus is applied for recording temperature in the present illustration. In practice it may be arranged that 35 the sending apparatus or unit is located adjacent an oven, as in a bakery, with a thermally sensitive member disposed in the oven and the recording unit may be located in the office or an executive room as when the apparatus is applied to 40 a large institution.

The sending unit 10, generally described, includes a motor 12, a thermally sensitive member 13 operatively carrying a contact 14, contacts 15, 16, one for each direction of the motor, these 45 contacts alternately engageable by the contact 14 of the thermally sensitive member, a contactor 16 driven by the motor 12 adapted to cooperate with a series of stationary contacts 17 for sending through recording impulses, the motor transmission including a transmission connection 18 to the two contacts thereof for the purpose of moving the same and disestablishing contact after a certain temperature change has been fully recorded.

Referring specifically to Figure 2, the motor 12 is mounted on a panel board 19. As an example, 110 volts are supplied to the motor through electrical leads 20 and 21. The sending motor requires around 90 to 100 volts for operation. One of the leads on the panel board, namely 20, is connected directly to the motor and the other, namely 21, is connected to the outer end of the thermally sensitive member 13. The member 13 is a Bourdon tube being filled with an expansible liquid whereby the tube coils and uncoils as the temperature changes occur and transmits movement.

The inner end of this coiled tube is fastened to the panel board by means of an anchorage 23. The inner end of the tube 13 includes an axially extended tube portion 13a which passes through the panel 19 and may be situated more directly in the environment of the heat, as through the side of an oven. The outer end of the Bourdon tube carries a contact arm 24 to which the lead 21 is connected, the outer end of the contact arm 24 including the contact 14 providing contact faces disposed at opposite sides thereof. These contact faces, respectively, are adapted to operate for making or breaking contact with the contacts 15, 15, constituted by the heads of screws mounted in a carrier block 25.

The carrier block 25 comprises a nut 26 translated by a motor driven screw 27 and arms 28 of insulation attached to the nut at each end thereof. Each of these arms mounts a respective contact 15, the heads of the contact screws being opposingly related. Each of the contact screws are connected to the motor by a respective lead 29 and the wiring of the reversible motor as shown in the wiring diagrams is arranged so that contact of the thermostatically operated contact with a particular contact screw produces a respective direction of motor operation.

The motor shaft 30 includes a pinion 32 driving a gear 33 pinned to the screw shaft 27. The screw shaft 27 is mounted in brackets 31 attached to the panel 19. Rotation of the screw shaft translates the carriage 25, the direction of the thread on the screw being such that upon a contact with one of the contact screws, the resultant rotation of the motor moves the particular contact screw 15 away from the contact for disestablishing the contact after the thermostatically moved contact becomes stationary and the full temperature change in the particular direction has been recorded. In order to prevent rotation of the nut 26 with the screw shaft, an arm 34 extends downwardly from the nut and includes a channel 35 engaging a guide 36 in parallelism with the screw shaft and secured to the panel 19.

The screw shaft carries the moving contactor 16 on its outer end, this contactor consisting of a piece of spring plate attached between cooperating nuts 37. The inturned end of the spring plate contactor moves over the series of segmental stationary contact plates 17 arranged concentrically relative to the screw shaft center. These segmental contact plates are attached to the screw shaft bracket.

The electrical energy is supplied to the movable contactor through an electrical lead 38 extending from one input or supply terminal 39 to the bearing bracket 31 of the screw shaft, the current flowing through the screw shaft to the contactor 16. From each segmental contactor plate an electrical lead 40 extends to a terminal 41 mounted on the panel. Thus it is seen that as long as the thermally sensitive member is active due to tem-

perature change, the contact 14 thereof is moved against one or the other of the screw contacts 15 and rotation of the contactor 16 continues, the contactor moving from one segmental plate 17 to another in its course of travel. It will be noted that these segmental contactor plates 17, of which there are three in this instance, are spaced apart sufficiently for the contactor finger to be entirely clear of any plate at the time of its passage from one contactor plate to another. The purpose of this will be made fully apparent at a subsequent point in this description.

There is a fourth terminal 44 on the panel board 19 to which the current is supplied from the other input or supply terminal 42 by an electrical lead 43. From these four terminals, electrical leads 45, 46, extend any distance required to the receiving or recording apparatus, the circuit from the sending unit being through terminal 42, lead 43, terminal 44 and lead 45 as one side and through terminal 39, lead 38, brackets 31, screw shaft 27, moving contactor 16, one of contacts 17, one of leads 40, one of terminals 41 and one of leads 46 as the other side of the circuit.

The recording unit 11 includes a pilot motor 25 of the reversible type, a recording instrumentality or stylus 47 actuated by a motor 48, an exemplification of which will be given later, and a double contactor 49 driven by the motor including diametrically opposite contacts 50, 50, connected to the respective sides of the motor wiring for reversal thereof. This plural contact on the motor shaft is adapted to engage segmental contact plates 51 of the same nature and general arrangement as the contacts 17 on the sending unit 10.

The recording instrument in this instance, described in detail, consists of a base plate 52 upon which is secured a face plate or support 53 for a rotating disc 54 having graph markings thereon including a related temperature scale and time chart, the degrees of temperature arranged from low at the inside circle to high at the outside circle, and the time chart constituted by hour lines on the line taken by a direct swing of the recording pencil 55 across the temperature indicating circles. This face plate 53 is supported by brackets 53a. The disc 54, which may be of cardboard or paper, is rotated on the face by means of a clock mechanism 56 having its shaft 57 extended through an aperture 58 in the face plate and rotatively connectable to the disc at its axis by means of a knurled nut 59 engaging the disc against a shoulder 60 of the shaft.

The motor 48 which controls the position of the recording finger is approximately a 30 volt motor and its control is accomplished through the segmental plates 51, and the contactors 50, 50 previously described.

The finger 61 of the recording device 47, which carries the pencil 55 or a writing instrumentality of any sort, is mounted on a pivot rod 62 at its lower end and includes a hub 63, to which hub a second finger 64 is attached, this finger including a longitudinally disposed slot 65 in its outer end engaged over a pin 66 extending from a nut 67 translatable mounted on a screw shaft 68 driven by the motor 48. The motor shaft 69 includes a worm 70 driving a worm wheel 71 pinned on the screw shaft 68. The screw shaft 68 is mounted in bearing brackets 72 attached to the base panel 52 of the unit.

Upon one end of this shaft and associated with the stationary contacts 51 mounted on one of the bearing brackets 72 are the contactors 75

50, 50 previously referred to. The contactors 50, 50 are disposed at respective sides of the bearing bracket 72 and are suitably insulated from each other and from the shaft. Each transmits electrical energy to the motor through a respective brush 73, 73. These motor control contactors 50, 50 each consist of a blade having an inturned outer end riding upon the contact plates 51 attached to the bearing bracket or panel 72. Since this bearing bracket is formed of insulating material, the contact plates are always insulated from each other. The contact plates 51 are sectional, each including sections disposed upon the respective sides of the panel 15 or bearing brackets. These sections are duplicates as to length and position and are electrically joined and fixed to the panel by means of screws 74 connecting the same through the panel. The mountings for contactors 50, 50, in each instance, consist of an insulated bushing 75 engaged directly upon the screw shaft and including a headed end lying against the inner face of the contactor. The contactor has a hub 76 disposed upon the bushing 75 upon the periphery of which hub a brush 73 in the form of a spring blade is disposed. In the instance of the inner assembly, a shoulder is provided on the screw shaft and a washer 77 of insulation lies against this shoulder, the particular contactor assembly being held against this washer by means of a nut 78 screwed onto the shaft. In the instance of the outer assembly, the bushing 75 is engaged against another washer 81 of insulation lying against a shoulder of the screw shaft and a nut 80 is screwed onto the end of the shaft securing the entire assembly in place.

Each of the segmental and sectional plates has an electrical lead 82 connected thereto extending from terminals 83 on the base panel 52. The terminals 83 are connected to the sending unit 10 by means of the leads 46, any one of these connections representing one side of the current flow from the sending device. The contactors 50, 50 on the receiving device are diametrically related so that they bear upon different contacts 51 of the stationary series. The brushes 73 which are attached to the base panel of the unit are connected to the wiring of the motor by leads 84 for respective directions of drive thereof. The other side for the current flow to the motor 48 comes through the lead 46 from the sending device to a terminal 85 on the panel 52 of the receiving unit 11 and thence to the motor 48 through a lead 86.

55 Operation of the system

The drawings (see Figure 1) illustrate the device at rest, each of the respective contactors 14, 50, 50, on the sending unit 10 and the receiving or recording unit 11 having coasted from one contact to the next adjacent contact, the inertia of the motors 12, 48, being sufficient for this purpose. The swinging contact 14 carried by the thermally sensitive element 13 on the sending unit 10 is poised midway between the reversing contacts 15, 15 at this time.

As the temperature rises or falls and the thermally sensitive member is effected, the swinging contact 14 thereof moves into contact with either one or the other of the contacts 15, 15, carried by the carrier 25. This establishes a circuit through to the motor 12 either for right or left hand drive, the current travelling to the motor through the direct connection 28 and through the connection 21 to the contact arm 24 of the thermally sensi-

tive member, thence passing from contact 14 into one or the other of the contacts 15 and to the particular wiring of the motor 12 by way of one of the leads 29. This starts the motor in one or the other directions and the screw shaft 27 is thereby rotated moving the contactor 16 the length of the particular stationary contact 17 on which it is resting at the time, whereupon it clears that contact and touches the next contact 17.

It will be noted that the contactor 16 of the sending unit 10 and the contactors 50 of the receiving unit are related to provide that the contact 17 upon which the contactor 16 of the sending unit first moves connects the electrical energy to a dead contact 51 of the series on the receiving unit, that is to say, one which is not contacted at the time by either of the contacts 50. However, as the contactor 16 leaves the particular contact 17 and engages the next contact 17, it will then establish an electrical connection from the main line input terminal 39 through the particular contact 17, thence through a particular electrical connection 46 between the units to the second contact 51 of the receiving unit which, due to the fact that one of the pair of contactors 50 of the receiving unit is resting thereupon, connects the current through said contactor 50 to the particular side of the receiving or recording motor 48 which is active through its transmission for causing movement of the recording finger 61 swinging the same in an arc generally radially relative to the rotating recording disc drawing thereupon a line indicating the rise or fall in temperature.

It is arranged that the motor 12 of the sending unit 10 will not operate when the motor 48 of the receiving unit is operating due to voltage and resistance conditions, which will be hereinafter described, so that the moment the contactor of the sending unit establishes the circuit for the impulse to the receiving motor, the sending motor stops momentarily. In the preceding description, the movement of the respective contactors has been assumed to be clockwise, it being apparent that if the swinging contactor 14 of the thermally sensitive element 13 has moved to the opposite contact 15, anticlockwise movement of these contactors would have resulted and the current flow would have been established to the receiving or recording motor 48 by way of the third contactors 17, 51 of the respective series.

Going back to the first description, it will be apparent that when the receiving or recording motor 48 has been set in motion, it will move, by means of the shaft 68, the contactors 50, 50 which control it until the particular one being described leaves the second contact of the series of the recording or receiving unit, at which time the recording motor will stop for the reason that the next contact is a dead one, that is, not connected through to the main line by way of a contact 17 of the sending unit.

As soon as the recording motor 48 stops, the sending motor 12 will again start, since there is then sufficient voltage for operation, and the contactor 15 thereof will move to the third contact 17 in a clockwise direction. This again establishes the circuit to the receiving unit motor 48 through the contact 17, lead 46, by way of the same contactor 50 of the receiving unit which has been effective and thence through the third contact 51 whereupon a second power impulse will occur for further movement of the recording finger.

These intermittent motor operations will occur

- cur as long as the thermally sensitive member is effected by temperature change and is continuing a rise or fall since the swinging contact will be continually urged against the particular contact 15 even though the sending motor is effective for slowly drawing the contact 14 away from the swinging contact, the pitch of the screw 27 being proportioned for a slow movement of the nut carried contacts 15, 15.
- 10 The moment the rise or fall of temperature ceases, the sending motor 12 will be effective for breaking the contact between contacts 14 and 15 and disestablishing the circuit to the sending motor by its own action. The swinging contact 14 is related to the contact screws 15, 15 so that a very slight movement thereof is effective for recording a temperature change, since the making and breaking of contact requires very little movement, thus resulting in a very sensitive recording or display of temperature. It is apparent that the thermally sensitive element 13 may be of any type desired and capable of imparting a motion to a particular double contact along the lines of that described.
- 15 It is necessary that the sending motor pause or operate intermittently for preventing the contact 16 operated thereby from running ahead of the contactors 50, 50 of the receiving device and for keeping these contacts in perfect relation for establishing the successive circuits through the respective electrically connected stationary contacts 17, 51, of the units. Therefore, as stated before, the sending motor and the receiving motor cannot operate concurrently. As 20 a practical electrical arrangement for accomplishing this result a resistance 90 of 75 ohms is inserted in the main line, this resistance being inserted in front of both of the motors. The larger motor 12, namely the sending motor, requires 90 volts or over for operation.
- 25 This motor 12 is calculated at a resistance of approximately 400 ohms. Therefore, the drop across resistance 90 is 17.4 volts (see later equations and Figures 8 and 9 of the drawings) and the input voltage to the sending motor is 92.6 volts. Since the sending motor will operate on 90 volts or more, the voltage 92.6, being the maximum supply to the sending motor, will be sufficient for operating this motor.
- 30 However, when the contact 58 of the recording unit closes the circuit through to the recording motor 48, thereby shunting the sending motor, neglecting the conductance of the sending motor, the voltage will be as follows: Since the receiving motor or recording motor 48 is calculated to operate on a voltage of from 25 to 30 volts and has been arranged at a resistance of about 25 ohms, the voltage drop through the resistance 90 figures at 82.5 volts and the voltage across the motors at 27.5 volts. Since the voltage drop through the resistance 90 is now 35 82.5 leaving only 27.5 volts input to the sending motor 12, the sending motor is inoperative. Therefore, the two motors work intermittently and alternately, the sending motor clearing one contact which requires a certain amount of movement equivalent to about one-third revolution of the shaft and makes another, the making of the second contact establishing the circuit to the recording motor which operates as long as a particular contact is maintained which is equivalent to about one-third revolution of the contactor driving shaft of this unit.
- 40 Otherwise stated, the sending motor stops due to lack of sufficient voltage to operate it when

the receiving motor is connected. The voltage applied across the terminals 39 and 42 can be considered as constant, say at 110 volts. When the sending motor 12 with the resistance of 400 ohms is connected across the line in series with resistor 90 of 75 ohms, and motor 48 is disconnected, as shown in Figure 8, the 110 volts are divided into a drop of 17.4 volts across the resistor 90, and 92.6 volts across the resistance motor 12. Since this motor requires over 90 volts, it will run with this connection. If the motor 48 with a resistance of 25 ohms is connected in parallel with motor 12, the combination in series with the resistor 90, as shown in Figure 9, motor 12 will not run. The motor, resistance of 400 ohms, of 400 and 25 ohms respectively, in parallel have a series resistance equivalent to 23.5 ohms, making the total resistance across the line, the 75 ohms of resistor 90, plus the 23.5 ohms equivalent resistance which is 20 98.5 ohms. The current through resistor 90 at 110 volts is 110 divided by 98.5 or 1.12 amperes. The voltage drop across resistance 90 is 1.12 times 25 75, or 83.7 volts, leaving a voltage drop of 26.3 across each of the motors 12 and 48. Since motor 12 requires 90 volts or more, it will not run, but motor 48, requiring from 25 to 30 volts, will run on the 26.3 volts available. The increase in current, due to the current requirements of motor 48, has increased the voltage drop across resistor 90 to such an extent that the remaining 30 volts of the 110 volts of the line are insufficient to operate motor 12. Thus the circuit which comprises the resistance of motor 48 alternately connected in parallel with the resistance of motor 12 constitutes an electrical interlock which prevents the operation of motor 12 during the operation of motor 48.

45 For further understanding of the circuits and voltage arrangement accomplishing the alternate operation of the motors, reference is made to Figures 8 and 9 for the following equations.

40 From Figure 8 the following equations are drawn which will explain in detail the voltages effective for permitting operation of the sending motor:

$$C_1 = \frac{75}{475} \times 110 = 17.4 \text{ volts}$$

$$C_2 = \frac{400}{475} \times 110 = 92.6 \text{ volts.}$$

50 These equations are true when the recording motor is in open circuit and the sending motor is operative. When the circuit is closed to the recording or receiving motor, referring to Figure 9, the 55 equations neglecting the resistance of the motor 12 will be as follows:

$$e_1 = \frac{75}{100} \times 110 = 82.5 \text{ volts}$$

$$e_2 = \frac{25}{100} \times 110 = 27.5 \text{ volts.}$$

60 These equations are based on the voltages coming through the respective input leads and the respective resistances when the entire current flow is through the sending motor and when a portion of this is shunted through the receiving or recording motor. It will be apparent that due to this wiring arrangement, the synchronized action of the units is always maintained and more particularly the relation of the thermally sensitive element and the recording finger is always maintained.

Having described my invention, I claim:

1. The combination with a temperature recording device of a thermally sensitive element including a movable contact, a motor, electrical connections to said motor, a resistor in one of said electrical connections, one of said electrical connections including said movable contact, a pair of motor control contacts alternately engageable by said movable contact for starting and 10 direction control of said motor in reversing directions, means driven by said motor for disestablishing contact between said motor control contacts and said movable contact, a contactor driven by said motor, a series of contacts successively and independently engageable by said 15 contactor, a second set of contacts located at the point of temperature record corresponding in number to the first set, the corresponding contacts of said sets of contacts respectively in electrical connection, a motor driven contactor element for traversing the contacts of said second set, said contact element normally out of phase one contact with respect to the contactor of said first set of contacts, a motor driving said contact 20 element and electrically connected thereto for effecting its own stopping control, said second series of contacts arranged relative to said contact element whereby contact between said element and a contact of the series is always maintained, said second set of contacts and said contactor element constituting a switch controlling the completion of the circuit of the motor driving the same through a circuit including a contact and the contactor of said first series, said second 25 motor when in electrical connection with said second contacts arranged to be in parallel with said first motor, and said motors when parallel connected arranged to be in series with said resistor, said first motor requiring substantially 30 line voltage for operation, said second motor requiring relatively less than line voltage for operation, said motors having resistances adapted when connected in parallel with each other and in series with said resistor to reduce the 35 voltage to a value sufficient to operate only the second motor and insufficient to operate the first motor.

2. Switchgear for remotely electrically indicating physical change, comprising, a pair of 40 multiple switches, each comprising a plurality of contacts and a contactor element for traversing the same, the respective contacts of said switches respectively in electrical connection, motors for respectively driving each of the contactors of said switches, said motors in common 45 partial circuit connection, a resistance included in the circuit to one of said motors, the contactor of one of said switches electrically energized, the contactors of said switches normally out of phase 50 one contact, a pilot switch having an element responsive to physical change alternately cooperating with oppositely arranged contact elements for starting and direction control of one of said motors in reversing directions, said 55 oppositely arranged contacts mounted for unitary 60

movement to disrupt and alternate motor direction control through said pilot switch element responsive to physical change, the motor of said second switch in circuit completing connection with said first motor through the contactor of 5 said second set of contacts and driving said second contactor to effect its own stopping control, said motors electrically connected to be in parallel when said partial common circuit is completed through said second switch and in series 10 with said resistance, said second motor requiring comparatively less line voltage for operation than said first motor, whereby the magnitude of the resultant voltage in the circuit when the motors are so connected is insufficient for operation of 15 said first motor but sufficient for operation of said second motor.

3. In an apparatus of the type described, an electric motor driven switch controlling a plurality of controlling circuits, a second electric motor 20 driven switch, the corresponding poles of said motor driven switches respectively in circuit connection, a thermo pilot switch having a thermo element alternately cooperating with oppositely arranged contact elements for starting and direction 25 control of one of said motors, said contacts mounted for unitary movement to disrupt and alternate motor direction control through said thermo switch element, said motors in common partial circuit connection, one motor driven 30 switch controlling the completion of the circuit to the other motor through said switch of said second motor in reversing directions for operative control, the operation of said second motor through its switch effecting its own stopping control, 35 the installation of the second motor into the circuit reducing voltage potential in the entire circuit to a value insufficient to drive the motor subject to thermo pilot switch control.

4. In an apparatus of the type described, an 40 electric motor driven switch controlling a plurality of controlling circuits, a second electric motor driven switch, the movable elements of said switches normally out of phase one contact in either direction, the corresponding poles of said 45 switches respectively in circuit connection, a thermo pilot switch having a thermo element alternately cooperating with oppositely arranged contact elements for starting and direction control of one of said switch motors, said contact elements mounted for unitary movement by the 50 motor controlled thereby, to disrupt and alternate motor direction control through said thermo switch element, said switch motors in common partial circuit connection, one motor driven 55 switch controlling the completion of the circuit to the other motor through said switch of said second motor in reversing directions for operative control, the operation of said second motor through its switch effecting its own stopping control, 60 the installation of the second motor into the circuit reducing voltage potential in the entire circuit to a value insufficient to drive the motor subject to thermo pilot switch control.

CURTIS F. MITCHELL. 65
